UNITED STATES PATENT OFFICE.

LEON J. HARVEY, OF PLOVER, WISCONSIN.

GRAIN-SCOURER.

SPECIFICATION forming part of Letters Patent No. 323,035, dated July 28, 1885.

Application filed April 23, 1885. (No model.)

To all whom it may concern:

Be it known that I, LEON J. HARVEY, a citizen of the United States, residing at Plover, in the county of Portage and State of Wisconsin, 5 have invented certain new and useful Improvements in Grain-Scourers, of which the following is a full, clear, and exact description, reference being had to the accompanying drawings, forming part of this specification, in 10 which—

Figure 1 represents a vertical sectional view of a grain-scouring machine embodying my improvements. Fig. 2 represents a cross-sectional view on the line $x x$ of Fig. 1. Fig. 3 15 is a detail of one of the beaters. Fig. 4 is a detail in perspective of the inner cylinder, showing the beaters and means for adjusting the same.

My invention relates to grain-scourers; and 20 it consists in the construction and combinations of devices hereinafter described and claimed.

To enable others skilled in the art to make 25 and use my invention, I will now describe the exact manner in which I have carried it out.

In the said drawings, A represents a frame of usual construction, in which the various working parts of my machine are mounted.

B represents a vertical shaft suitably mounted 30 in the cross-pieces $a a'$, and provided with a band-pulley, b , and a gear-wheel, c , which, operated by said vertical shaft, revolves the outer cylinder, G, as I shall hereinafter fully describe.

Within a suitable casing, C, in the upper 35 part of the frame A, is mounted a suction-fan, D. This fan receives its motion from the shaft B, and it has a direct connection with the interior of the cylinder through the medium of flues connecting with the fan D through openings f , formed in its sides and terminating in vertical flues e , which enter the cylinder-casing, as shown in Fig. 1.

E represents a vertical shaft, the lower end 45 of which has a bearing in a step or cross-bar, g , and the upper end passes through and is permitted to revolve in a cross-bar, g' , in the upper portion of the frame. Upon the shaft E is rigidly mounted a cylinder, F, which consists, essentially, of the end disks, h and h' , and 50 vertical beaters h^2 . The disk h receives the grain upon its upper surface, and is provided

with a series of pins or lugs, i , which engage and evenly distribute the grain during the rotary movement of the cylinder. The beaters h^2 , which constitute a portion of the cylinder, are secured to the end disks at an angle or diagonally to the outer revolving cylinder, G, and they are secured so as to have an adjustment toward or from the exterior cylinder, this 60 adjustment being made to accommodate different kinds of grain. This adjustment is accomplished by the mechanism illustrated in Fig. 4. In this figure, it will be observed, the beaters h^2 are attached to the end disks, $h h'$, by pins 2, which permit the beaters to swing in or out. There is then placed inside this cylinder, about half way, a collar, B', with arms or pins 3, projecting into each beater, and with a hub which sets on the lower disk, h' , and as 70 the collar is turned the arms or pins 3 move the beaters toward the outer cylinder. This collar B' is held in place by a set-screw, 5, at the lower end, the set-screw being made accessible by hand-holes 6 in the bottom of the 75 cylinder and the openings in the outer cylinder which discharge the grain. The beaters h^2 , when set diagonally, as in the present case, have a tendency to retard the falling grain. The beaters h^2 are corrugated their entire 80 length, and the spaces between the beaters are equal to about one-half their width. These dimensions I prefer to use in the construction of my machine, although they may be changed without departing from the spirit of my invention. The outer cylinder, G, has a hollow 85 sleeve, H, and a disk, I, secured to said sleeve. A gear-wheel, K, secured to the outer cylinder forms the upper end of the cylinder, and this gear-wheel meshes with and receives its 90 motion from the gear c on the vertical shaft B.

Extending upwardly from the gear K is another hollow sleeve, L, which engages the bottom of a suitable hopper and permits the grain to pass between the shaft and sleeve L and 95 thence through the center of the gear to the distributor-disk.

The cover for the outer cylinder consists of the strips M, which are perforated their entire length with elongated slots m , and on their 100 inner peripheries are formed with vertical corrugations n , as shown in Fig. 2.

Around the inside of the outer cylinder, and projecting inwardly a slight distance, are suit-

able flanges, *l*, which prevent a too rapid descent of the grain through the machine, and the bottom disk, *I*, has a series of openings, *g*³, through which the grain passes, after it has been scoured, by being thrown centrifugally against the sides of the corrugated outer cylinder. The grain falling into the chutes *O*, directly beneath the disk, is discharged into a suitable receptacle.

- 10 The operation of my machine is as follows: Motion is imparted to a pulley, *P*, on the shaft *E*, which operates the inner cylinder, *F*, and band *r* communicates the motion of shaft *E* to the shaft *B*, which operates the suction-fan *D* and gear-wheel *c*. The gear-wheel *c*, engaging the gear *K*, causes the outer cylinder to revolve, but in a direction opposite to the revolution of the inner cylinder, which is fast upon the shaft. This being the case, the grain which 15 passes through the upper sleeve of the outer cylinder is discharged upon the top of the inner cylinder, receives a scouring by the opposite revolutions of the cylinders, and is discharged from the machine in a clean condition.
- 20 25 The chaff and light foreign substances, being carried upward by the suction, may be discharged in the usual manner.

Having thus described my invention, what I claim as new, and desire to secure by Letters 30 Patent, is—

1. The combination, with a vertical outer cylinder having a gear-wheel, *K*, of an inner cylinder revolving in a direction opposite to the rotation of the outer cylinder and provided 35 with a hollow sleeve, *H*, and the adjustable beaters *h*², the pinion *c*, shafts *B* and *E*, and

means for operating the shafts, substantially as described.

2. The combination, with an outer cylinder having its circumference slotted its entire 40 length and provided with an interior corrugated surface and the horizontal flanges *l*, of an inner oppositely-revolving cylinder having a sleeve, *H*, supported in the frame of the machine, and the corrugated adjustable beaters *h*², 45 the inclined chutes upon each side of the sleeve *O*, the gears *c* and *K*, the shafts *B* and *E*, and means for operating said shafts, substantially as herein described.

3. The slotted vertical cylinder *G*, having a 50 hollow sleeve, *L*, through which the grain passes from the hopper, a gear-wheel, *K*, and a perforated disk, *I*, forming the lower end of said cylinder, in combination with an inner cylinder having the end disks, *h* *h*', the adjustable corrugated beaters *h*², a hollow sleeve, *H*, supported in the frame, and means for driving the cylinders in opposite directions, substantially as herein described.

4. A grain-seourer comprising the frame *A*, 60 shafts *B* and *E*, gears *c* and *K*, the cylinders *F* and *G*, adjustable beaters, a suction - fan mounted on the shaft *B*, a fan-case having a discharge-opening, and the horizontal and vertical flues *d* and *e*, the latter communicating 65 with the interior of the frame outside of the cylinder *G*, substantially as herein described.

LEON J. HARVEY.
